ATTORNEYS

UNITED STATES PATENT OFFICE.

SAMUEL G. SUPPLEE, OF EAST ORANGE, NEW JERSEY.

DENTURE-ATTACHING DEVICE.

Application filed March 18, 1921. Serial No. 453,205.

To all whom it may concern:

Be it known that I, SAMUEL G. SUPPLEE, a citizen of the United States of America, residing at East Orange, Essex County, New Jersey, have invented a new and useful Denture-Attaching Device, of which the following is a specification.

My invention relates to a denture attaching device and is similar in some respects to the construction shown in my Patent #1,324,476.

It is an object of my invention to provide a denture attaching device which may be cheaply constructed and which will serve to frictionally hold a removable denture.

In general, it is the object of my invention to simplify and improve the construction of means for holding removable dentures in place.

In the preferred form of my invention, I provide a post to be attached to one denture member and a sleeve to be attached to another denture member and receiving said post. The post is provided with a spring for frictionally engaging the sleeve, and the spring is preferably adjustable to vary the degree of frictional engagement with the inside of the sleeve.

In the drawings, I have shown for illustrative purposes only, various forms of my invention.

Fig. 1 is a partially diagrammatic view showing dentures with one embodiment of my invention applied thereto.

Fig. 2 is a blank for forming part of a post member.

Fig. 3 is a perspective view showing a post and sleeve separated from each other.

Fig. 4 is a section taken substantially in the plane of the line 4—4 of Fig. 3.

Fig. 5 is a view of a different form of blank.

Fig. 6 is a view similar to Fig. 3, but showing a different form of spring member.

Fig. 7 is a section taken substantially in the plane of the line 7—7 of Fig. 6.

Fig. 8 is a view similar to Figs. 3 and 6 and showing a different form of the invention.

Fig. 9 is a section taken substantially in the plane of the line 9—9 of Fig. 8.

Fig. 10 shows a modified method of attachment.

In Fig. 1 of the drawings, 5—5 indicate stationary or abutment dentures. 6—6 indicate removable dentures to fit between the

fixed dentures 5. To one of the dentures is fixed a post 7 and to one of the other corresponding dentures is fixed a sleeve 8 to fit over the post 7 for securing the removable dentures in place.

In Fig. 3, 10 designates a sleeve member similar to the sleeve members 8 in Fig. 1 and the sleeve is preferably provided with a slot 11 along one side. The post 65 which is received in the sleeve 10 may comprise an end pin 12 and an outer plate 13 bent around the pin. The blank of the plate 13 which is shown in Fig. 2 is provided with slits substantially in the form of the letter H. When the blank 13 is bent around the pin 12, the parts 14 adjacent one of the slits form spring members to frictionally engage the inside of the sleeve. These spring members are preferably bowed or 75 rounded intermediate their edges as at 15 and the edges 16 are preferably in substantially the same plane as the remainder of the blank. It will thus be seen that the post may be slid into the sleeve member and with the edges 16 in the same plane as the remainder of the blank there will be no shoulders to engage the upper end of the sleeve and prevent the insertion of the post. The bowed out or projected portion 15 provides the frictional engagement for holding 85 the post within the sleeve. It will be seen that in the form shown in Fig. 3 a knife blade or other instrument may be inserted between the adjacent edges of the spring 90 members 14 to bend the springs outwardly for adjusting them to vary the degree of friction with the sleeve.

Figs. 5, 6 and 7 show a form of my invention differing from that previously described 95 mainly in the form of blank and spring. The sleeve 18 in this case may be similar to the sleeve 10 previously described. The blank 19 is provided with an aperture 20, the same being rectangular in the specific 100 form shown and when the blank 19 is bent around or applied to the pin 21, the aperture 20 will leave the pin exposed intermediate its ends. A separate plate or sleeve spring 22 is applied to the post in the aperture left in the blank. The two ends 23 of the spring are relatively close together and this spring as in the previous case may be adjusted by inserting an instrument between the ends of the spring 22. At a point 110 intermediate the ends of the spring 22, there is provided a bowed up portion or hump 24,

and the upper and lower edges of the spring 25 are preferably in the same plane as the blank 19 surrounding the pin so that no shoulders are left to prevent the insertion 5 of the post into the sleeve.

In Figs. 8 and 9 is shown still another form of my invention. In this form the post proper 26 is formed of a substantially half round section, and the sleeve 27 preferably 10 conforms in general to the section of the post proper. A leaf or plate spring 28 is provided on the post and preferably partially surrounds the latter. If desired, the spring may be secured to the post as by 15 means of a pin 29. Part of the spring intermediate its upper and lower edges is preferably bowed out or provided with a hump 30 to frictionally engage the inside of the sleeve. The spring may be set into 20 a recess 31 in the post and the edges of the spring are preferably flush with the surface of the post so that any projecting edges which would prevent the insertion of the post in the sleeve are avoided.

25 In Fig. 10 the sleeve 32 is secured in a cavity in the tooth as by means of an inlay 33. The post 34 is secured to the removable denture in any suitable manner. If desired the inside of the sleeve may be beveled or 30 humped as at 35 to provide additional friction for the spring.

In each of the posts disclosed, there is a plate or projection extending from one side. It is to be understood that this is merely 35 one means of securing a post to a denture, and the projection may be cut off to the desired length or dispensed with entirely if desired. Both posts and sleeves may be secured to the dentures in any known or de- 40 sired manner, and I do not wish to be limited to any particular shape of post and sleeve.

While I have disclosed specific embodiments of my invention, I wish it to be understood that changes and modifications may be

made within the scope of the claims appended hereto. 45

I claim:

1. In a denture attaching device, a sleeve member to be secured to one denture member and open along one side, a post to be 50 secured to another denture member and to fit within said sleeve, and a spring carried by and on the outside of said post and substantially surrounding the latter for frictionally engaging the sleeve, said spring being adjustable to vary the degree of frictional engagement with the sleeve. 55

2. In a denture attaching device, a post comprising a pin and a plate for supporting the pin, a sleeve for receiving said post and open along one side, and a plate spring carried by said post and partially surrounding the pin for holding the post and sleeve in assembled relation, said spring being adjustable to vary the frictional engagement 60 between the post and sleeve. 65

3. In a denture attaching device, a post member, a sleeve member for receiving said post and open along one side, and a plate spring carried by said post and partially 70 surrounding the same, said spring being bowed intermediate its edges and the edges lying in substantially the same plane as the post, said spring being adjustable to vary the frictional engagement with said sleeve. 75

4. In a denture attaching device, a sleeve open along one side, a post to be received by said sleeve, and a spring carried by and partially surrounding said post and having a part in position to be engaged by an instrument for adjusting the spring to vary the frictional engagement between the spring and sleeve, said spring engaging the inside surface of and being substantially completely within said sleeve when the post 80 and sleeve are assembled. 85

SAMUEL G. SUPPLEE.
